UNITED STATES PATENT OFFICE

JULIUS GROSSMAN, OF NEW YORK, N. Y., ASSIGNOR TO EAGLE LITES, INC., A CORPORATION OF NEW YORK

DESIGN FOR A BASE FOR LAMPS OR ANALOGOUS ARTICLES

Application filed August 3, 1929. Serial No. 32,294. Term of patent 3½ years.

To all whom it may concern:

Be it known that I, JULIUS GROSSMAN, a citizen of the United States, and a resident of 735 Walton Avenue, of New York, county of Bronx, and State of New York, have invented a new, original, and ornamental Design for a Base for Lamps or Analogous Articles, of which the following is a specification, reference being had to the accompanying drawing, forming a part thereof.

In the drawing:

Figure 1 is a front elevational view of the base for lamps or analogous articles; and

Figure 2 is a diagrammatic edge view of the same.

I claim:

The ornamental design for a base for lamps or analogous articles substantially as shown.

JULIUS GROSSMAN.
